UNITED STATES PATENT OFFICE.

EDWIN E. RAWSON, OF MONTREAL, QUEBEC, CANADA.

PICKER STICK FOR LOOMS.

Application filed March 25, 1927. Serial No. 178,400.

This invention relates to new and useful improvements in picker supporting devices for looms, and the object of the invention is to provide a strong and durable picker support which will be inexpensive to manufacture and maintain in operation.

A further object is to provide a support which will not be affected by atmospheric changes in the mill.

10 The picker supports at present in use are usually made of selected wood which must be of straight grain. These supports or sticks before being put into operation are subjected to a very severe test against warping, 15 and the sticks which do not pass this test are destroyed. It will be seen that this condition tends to keep the price of these sticks very high.

In my invention I overcome the above objections by forming the supports for the pickers of thin metal tubing, or drawn steel, which has not the same tendency to get out of shape during the operation of the loom.

In the drawings which illustrate my improved type of picker support in different forms;—

Figure 1 is a partial side elevation of a picker support with the picker (shown in dotted lines) attached thereto.

30 Figure 2 is a partial plan of the support shown in Figure 1.

Figure 3 is an enlarged sectional end elevation of the support taken on the line 3—3 Figure 2.

35 Figure 4 is an enlarged sectional end elevation of the support taken on the line 4—4 Figure 1.

Figure 5 is a side elevation of a modified type of support.

40 Figure 6 is a sectional end elevation taken on the line 6—6 Figure 5.

Figure 7 is an end elevation of the support shown in Figure 5.

Referring more particularly to the drawings, 45 11 designates my preferred form of picker stick, or support, which is made from a metallic tube of rectangular cross section, as shown in Figures 3 and 4. The support is preferably made tapering from the end 14 to the end 15. In the type shown in Figures 1 to 4 inclusive, the sides 16 and 17 are made wider than the top and bottom 12 and 13 at the end 14, and diminish in width more rapidly than the top and bottom towards the

end 15. The picker 18, which may be of any desired form, is secured to the smaller end 15. The end 14 is provided with an aperture 19, through which a bolt, or such like fastening device, is passed to secure the support to a rocker beam in the usual manner. 55 60

In the form shown in Figures 5 to 7 inclusive, the end 15^a is made of round tubular cross section and the picker 18^a is placed between a pair of spaced collars 20, which are pressed or forced on to the end of this support. The remainder of the support is made of rectangular tubular cross section with the sides 12^a and 13^a tapering outwardly towards a portion 21, in proximity to the end 14^a. The sides 12^a and 13^a are made with 70 their edges parallel to one another from the portion 21 to the end 14^a.

I do not desire to be understood as limiting myself to the types of supports shown in the drawings, as they are shown for illustrative purposes only and many modifications may be made in the shape of the supports without departing from the spirit of the invention. 75

The supports as shown, are inexpensive to manufacture and maintain in operation and, being made of thin tubing, are light and are not affected by atmospheric changes in the same manner as the wooden type of support or stick at present in use. By tapering the support in the manner herein described, the picker support is constructed to resist the maximum strain due to bending, as the greater depth at the end remote from the picker is the point where maximum bending occurs during the operation of the loom. It will be readily seen that a support made of thin metallic tubing tapering from one end to the other can be made resilient to absorb the shock or force exerted on the picker and its support when flying or driving a shuttle. 80 85 90 95

Having thus described my invention, what I claim is;—

As a new article of manufacture, a picker stick consisting wholly of a hollow drawn metal tube having a body portion of rectangular cross section gradually tapering toward one end and provided at said end with an integral extension of circular cross section adapted to receive a picker. 100 105

In witness whereof, I have hereunto set my hand.

EDWIN E. RAWSON.
